UNITED STATES PATENT OFFICE.

MARTIN MAIER, OF DETROIT, MICHIGAN.

DESIGN FOR A TRUNK-IRON.

SPECIFICATION forming part of Design No. 15,770, dated February 3, 1885.
Application filed October 24, 1884. Term of patent 7 years.

To all whom it may concern:

Be it known that I, MARTIN MAIER, of Detroit, in the county of Wayne and State of Michigan, have invented a new and useful Design for Trunk-Irons; and I do hereby declare that the following is a full, clear, and exact description thereof, reference being had to the accompanying drawings, which form a part of this specification.

Figures 1, 2, and 3 are perspectives of different forms of my iron, having the same general design.

My design relates to a trunk-iron.

A A represent irons of the particular class above referred to. A' is the central portion of the iron, which is of gracefully-broken outline and paneled faces, and in Figs. 2 and 3 is shown as provided along its longitudinal center with the projecting ridge a', bent at right angles, or substantially so, as shown.

B represents the end or strap sections of the iron. These end sections are substantially triangular in form, and are provided with holes a. Each end section, B, is also provided with an irregular recess or panel, b, substantially shield or heart shaped in form, which recess may be cut entirely through; or there may be a web partially filling the same.

All of the trunk-irons are ornamented in a similar manner, and correspond in design, size, or shape, so as to produce the desired harmony in appearance.

It will be seen that the leading features of my design consist in a central portion and end or strap sections substantially triangular in form, and provided with an irregularly-shaped recess and holes at points of the triangle.

What I claim is—

1. The design for a trunk-iron herein described, the same consisting of a central portion, as A', and triangular end sections, B, having a hole, a, at each point of the triangle, and an irregularly-sided recess, b, as shown.

2. The design for a trunk-iron herein shown and described, the same consisting, essentially, of the central portion, A', provided with the projecting ridge a', and the triangular end sections, B, having holes a, and a shield or heart shaped recess, b, as shown.

MARTIN MAIER.
